UNITED STATES PATENT OFFICE.

JACOB D. FLOMERFELT, OF TAFT, FLORIDA.

RAIL-TIE.

1,020,273.

Specification of Letters Patent. Patented Mar. 12, 1912.

Application filed May 26, 1911. Serial No. 629,533.

To all whom it may concern:

Be it known that I, JACOB D. FLOMERFELT, a citizen of the United States, residing at Taft, in the county of Orange and State of Florida, have invented new and useful Improvements in Rail-Ties, of which the following is a specification.

This invention relates to rail ties, and has for an object to provide a tie which will include a central longitudinally disposed arch member of a downwardly increasing diameter, the side walls of which forming tamping surfaces to be engaged against the ballast so that the tie will be held against sagging at either end.

Another object of the invention is to provide a tie which can be constructed from metal and wood, the respective elements of the tie being so arranged that the wood portions thereof will form an efficient cushion for the rolling stock.

A still further object of the invention is to provide a tie which will include means for securely holding the rails thereto.

In the drawings, forming a portion of this specification and in which like numerals of reference indicate similar parts in the several views: Figure 1 is a perspective view of the tie. Fig. 2 is a sectional perspective 25 view of a portion of the tie. Fig. 3 is a perspective view of one of the rail fastening plates. Fig. 4 is an inverted perspective view of the arch member. Fig. 5 is a transverse section taken on line 5—5 of Fig. 2. Fig. 6 is a section on line 6—6 of Fig. 1 showing the rail clamping devices engaged 35 with the rail.

My improved tie comprises the main elastic supporting members 1 which are preferably constructed of wood, being suitably spaced apart for the reception therebetween of the inverted V-shaped member 2. The inner surfaces of the members 1 are inclined downwardly in opposite directions, and as 45 illustrated, each member is of a downwardly decreasing dimension. The member is reversely formed, the same being of a downwardly increasing dimension, the oppositely inclined side walls 3 of which being engaged 50 directly against the inner surfaces of the members 1.

Combined chair and rail clamping plates 4 extend across the members 1 and 2, each plate having formed integrally therewith a 55 rail-clamping flange 5. Flanges 6 extend downwardly from the plates 4 and at the

ends of the members 1. The flanges 6 extend beyond the members 1 for effective anchoring engagement with the road-bed. The plates 4 are connected with each other 60 by an integral bar 7. This bar extends longitudinally of the members 1 and is disposed above the space between the walls 3 of the member 2, being provided in line therewith with suitable passages 8 to permit of the introduction of sand or a suitable ballast into the inverted V-shaped member. The bar 7 is provided with enlarged portions 9 from which extend vertical threaded studs 10. The inner rail 70 clamping members 11 are provided with horizontal portions 12 which are slidably mounted on the portions 9, as clearly shown. The horizontal portions 12 are provided with elongated slots 13 for the reception of the studs 10. Suitable nuts or clamping devices 14 on the studs 10 bear against the portions 12 so as to hold the movable clamping plates in their adjusted 75 positions relative to the clamping portions 80 5 hereinbefore described. The walls 3 of the inverted V-shaped member are connected with each other by integral webs 14' which divide the member into a plurality 85 of separate pockets. Immediately at the center the walls 3 are connected with each other by a substantially V-shaped member 15. This member is so constructed that it provides oppositely inclined tamping surfaces 16 which act in addition to the walls 3 of 90 the arch to cause the tie to take an effective purchase on the ballast. The plates 4 are provided with depending ears 17, and as illustrated, clamping bolts 18 are extended 95 through the ears and through the members 1 and the walls 3 of the tie.

From the construction described it will be seen that a very simple tie is provided which will be strong and durable, and which, in practice, can be relied upon as 100 means for positively preventing spreading or sagging of the rails.

The invention further provides means whereby the meeting ends of the rails can be securely supported upon the tie without the provision of the old and well known forms of fish plates or like connecting devices.

I claim:

1. A tie comprising a pair of spaced members, each of the said members having their inner surfaces inclined downwardly and be-

ing spaced to provide a central, longitudinally disposed space, being open throughout, an inverted V-shaped member positioned within the said space, the said member being of a formation substantially in configuration with the said space, and extending full length of the said space, the said inverted V-shaped member being open throughout, so as to permit the introduction 5 of sand or other suitable ballast, rail clamping means on the tie.

2. A tie comprising a pair of cushion members being spaced to provide a central longitudinally disposed space and being 10 open throughout, an inverted V-shaped member being open throughout positioned within the said space, rail clamping means on the tie, the said means comprising a pair of substantially L-shaped rail plates, supported by the opposite ends of the said tie, 15 20

the said plates being connected by a central longitudinally extending integral bar member disposed immediately above the said space, the said bar being provided with a plurality of alining passages adapted to 25 permit the introduction of sand or other suitable material within the inverted V-shaped member, each of the said rail plates being formed to provide a pair of depending ears adapted to engage the opposite 30 sides of the tie, a clamping bolt extended through the said tie in ears and adapted to retain the said clamping plates in an operative position on the tie.

In testimony whereof I affix my signature 35 in presence of two witnesses.

JACOB D. FLOMERFELT.
